WIRE CONNECTOR

Arthur O. Havens, Naugatuck, Conn., assignor
to Chase Brass & Copper Co. Incorporated,
Waterbury, Conn., a corporation

Application January 18, 1941, Serial No. 374,967

6 Claims. (Cl. 287—49)

The present invention relates to improvements in wire-connectors and more particularly to improvements in wire-connectors adapted for the connection of electric wires though not so limited.

One of the objects of the present invention is to provide a superior wire-connector which may be produced at a low cost for manufacture.

Another object of the present invention is to provide a superior wire-connector embodying a clamping-nut and in which the parts are so constructed and arranged as to automatically resist the loosening of the said clamping-nut when the same has been tightened to connect two wires.

A further object of the present invention is to provide a superior wire-connector which may be utilized to connect a branch-wire to a line-wire without requiring the disassembly of the nut-member from the body-structure.

With the above and other objects in view, as will appear to those skilled in the art from the present disclosure, this invention includes all features in the said disclosure which are novel over the prior art.

In the accompanying drawings, in which certain modes of carrying out the present invention are shown for illustrative purposes:

Fig. 1 is a perspective view showing one form of wire-connector embodying the present invention as installed upon a line-wire and serving to connect a branch-wire thereto;

Fig. 2 is a view in side elevation of the assembly shown in Fig. 1;

Fig. 3 is an underside view thereof;

Fig. 4 is a transverse sectional view taken on the line 4—4 of Fig. 2;

Fig. 5 is a central longitudinal sectional view taken on the line 5—5 of Fig. 2, but on a larger scale;

Fig. 6 is a central longitudinal sectional view taken on the line 6—6 of Fig. 5;

Fig. 7 is a perspective view of the group of four parts from which the complete wire-connector of the preceding figures may be constituted;

Fig. 8 is a view in central longitudinal section of the same character as Fig. 5, save that a modified form of wire-connector embodying the present invention is shown;

Fig. 9 is a central longitudinal sectional view taken on the line 9—9 of Fig. 8; and

Fig. 10 is a perspective view of the clamping-shoe of the structure of Figs. 8 and 9.

The structure of Figs. 1 to 7 inclusive

The particular wire-connector shown in Figs.

1 to 7 inclusive, includes a two-part body composed of two similar body-members respectively generally designated by the reference characters 15 and 16. Each of the said body-members is substantially semicircular in cross section, so that the respective inner faces thereof are flat, save that each is provided with a central longitudinal guide-rib 17 extending from the lower end of each body-member upwardly about half-way of the length thereof, as is shown particularly well in Fig. 7.

Each of the body-members 15 and 16 above referred to, includes a relatively-large head 18 at its upper end and a relatively-slender stem 19 formed integral with and depending from the said head. On its outer face, each of the body-members 15 and 16 is formed at the junction of its head 18 and its stem 19 with a downwardly-facing limiting-shoulder 20.

Extending through the head 18 of each of the body-members 15 and 16 from the inner to the outer face thereof is a branch-wire passage 21. The outer surface of the stem 19 of each of the said body-members 15 and 16 is formed with screw-threads 22 adapted to interfit with screw-threads 23 formed interiorly of a clamping-nut 24.

Interposed between the flat inner faces of the body-members 15 and 16 is a spacer or clamping-shoe generally designated by the reference character 25 and including a head 26 and an integral depending shank 27. Extending lengthwise of the upper surface of the head 26 of the clamping-shoe 25 is a concave or V-shaped groove 28, as is shown particularly well in Fig. 7.

At each of its opposite ends the head 26 of the clamping-shoe 25 extends beyond the adjacent end-walls of the shank 27 and thus provides at each of the respective opposite ends of the clamping-shoe a downwardly-facing shoulder 29 resting upon the upper face of the clamping-nut 24. Formed centrally in each of the respective opposite sides of the clamping-shoe 25 is one of two aligned guide-grooves 30—30. The said guide-grooves 30—30 extend vertically the full length of the clamping-shoe 25 and are dimensioned to respectively receive with a sliding fit the guide-ribs 17—17 formed integrally upon the respective inner faces of the body-members 15 and 16.

After the component parts of the wire-connector (illustrated particularly well in separated relationship in Fig. 7) are assembled together as illustrated in Figs. 1 to 6 inclusive, the lower end 55 of the shank 27 of the clamping-shoe 25 is upset

on each of its respective opposite sides to provide limiting-fingers 31—31 having inclined upper surfaces, as is shown particularly well in Fig. 6, and adapted to have wedging engagement respectively with inclined limiting-surfaces 32—32 respectively formed on the lower inner corners of the body-members 15 and 16.

After the body-members 15 and 16, the clamping-shoe 25 and clamping-nut 24 have been assembled as described, it is preferred that the lowermost threads on the said body-members be upset as at 33 to thereby prevent the accidental disassembly of the elements. The upsetting of the threads as at 33—33 create, in effect, a stop-abutment limiting the relative downward movement of the clamping-nut 24 relative to the body-members 15 and 16.

When the elements are all assembled, the body-members 15 and 16 are held in spaced relationship by the clamping-shoe or spacer 25, so that the threads upon the respective outer faces of the stems 19—19 of the said body-members are held in engagement with the threads 23 in the interior of the clamping-nut 24. As thus positioned in spaced relationship, the body-members 15 and 16 provide between them, at a location above the clamping-shoe 25, a notch-like line-wire passage adapted to receive a line-wire such as 34. The assembled device may be slipped laterally over the said line-wire 34 while the clamping-nut 24 is retarded slightly downwardly beyond its normal clamping position, and afterward a branch-wire such as 35 may be inserted through the respective and aligned branch-wire passages 21, as is especially well shown in Fig. 1. The clamping-nut 24 may now be threaded upwardly toward the respective heads 18—18 of the body-members 15 and 16 to carry the clamping-shoe 25 with it until the line-wire 34 resting in the groove 28 in the upper surface of the said shoe has had its upper face tightly impinged against the under face of the transversely-extending branch-wire 35. Under these conditions, the branch-wire 35 acts as a key to prevent the wire-connector as a whole from becoming separated from the line-wire 34.

Preferably, the parts are so proportioned that when the line-wire 34 and the branch-wire 35 have been brought into tight electrical and mechanical engagement, the limiting-fingers 31—31 of the clamping-shoe 25 will have been brought into wedging engagement with the inclined limiting-surfaces 32—32 of the respective body-members 15 and 16.

Due mainly to the fact that the body-members 15 and 16 are separate and distinct elements capable of movement relative to each other, the tightening of the clamping-nut 24 as above described, will not only effect the tight mechanical and electrical inter-engagement of the line-wire 34 and the branch-wire 35, but the tendency of the upper or head-ends 18—18 of the said members to spread slightly under the clamping strain, will in turn so tightly grip the clamping-nut 24 as to render the same substantially immune to becoming loosened by vibrations almost incessantly occurring in suspended electrical conductors. Furthermore, the wedging engagement between the inclined limiting-fingers 31—31 of the clamping-shoe 25 with the limiting-surfaces 32—32 of the respective body-members 15 and 16, will further tend to spread the lower end of the said body-members to a degree sufficient to assist in maintaining the clamping-nut 24 against becoming loosened.

From the foregoing it will be seen that it is possible to connect two wires such as the wires 34 and 35 without requiring the demounting of the clamping-nut 24 or its equivalent from the assembly. Under these conditions, the wire extending through the branch-wire passages 21—21 of the respective body-members 15 and 16 acts as a key which prior to its insertion in no way interferes with the fitting of the wire-connector over a continuous line-wire such as 34. On the other hand, however, after the insertion of the branch-wire 35, the line-wire 34 is no longer free for demounting from the wire-connector and vice versa.

15 *The structure of Figs. 8, 9 and 10*

In Figs. 8, 9 and 10 is shown a wire-connector comprising two body-members 36 and 37, each having a lower threaded portion 38. The lower respective threaded portions 38 of the body-members 36 and 37 fit within a cup-shaped clamping-nut 39 and like the body-members 15 and 16 before described, each of the body-members 36 and 37 is formed in its upper end with a transverse branch-wire passage 40.

20 Interposed between the body-members 36 and 37 above referred to, is a spacer 41 having a head 42 and a cylindrically-contoured depending-shank 43 formed integral therewith. The 30 said shank 43 rests upon the upper surface of the end wall of the clamping-nut 39 and is provided centrally with a relatively-slender stem 44 extending downwardly through the said end wall and upset at its lower end as at 45 to retain the members 39 and 41 in assembled relationship.

35 The spaced-apart body-members 36 and 37 provide between them a notch-like passage in which may be located a line-wire 46 and across 40 which may extend a branch-wire 47 accommodated in the branch-wire passages 40—40 before described.

45 When the clamping-nut 39 is tightened, the upper edge of the said clamping-nut and the spacer 41 will be forced against the line-wire 46, which latter, in turn, will be forced against the branch-wire 47 to thereby serve to both electrically and mechanically interconnect the two said wires.

50 Both of the forms of the present invention herein chosen for illustration, possess the same fundamental advantages and, as may be noted by reference to Figs. 5, 6, 8 and 9, the given branch-wire may be engaged with its complementary line-wire so tightly as to cause each thereof to more or less deform and indent the other.

55 The invention may be carried out in other specific ways than those herein set forth without departing from the spirit and essential characteristics of the invention, and the present embodiments are, therefore, to be considered in all respects as illustrative and not restrictive, and all changes coming within the meaning and equivalency range of the appended claims are intended to be embraced therein.

60 I claim:

65 1. A wire-connector including in combination: two complementary physically-distinct body-members arranged side by side in spaced relationship with respect to each other to provide a passage therebetween for the reception of a line-wire and of a spacer, each of the said body-members being formed with an outwardly-facing threaded portion and each thereof being formed

with a branch-wire passage extending in a direction crosswise of the passage between the two said body-members and intersecting the said passage therebetween; a clamping-nut engaging with and embracing the respective threaded portions of the two said body-members; and a spacer interposed between the two said body-members to hold the respective threaded portions thereof in engagement with the said clamping-nut.

2. A wire-connector including in combination: two complemental physically-distinct body-members arranged side by side in spaced relationship with respect to each other to provide a passage therebetween for the reception of a line-wire and of a spacer, each of the said body-members being formed with an outwardly-facing threaded portion and each thereof being formed with a branch-wire passage extending in a direction crosswise of the passage between the two said body-members and intersecting the said passage; a clamping-nut engaging with and embracing the respective threaded portions of the two said body-members; and a clamping-shoe engaged by the said clamping-nut and constructed and arranged to be moved thereby toward the branch-wire passages respectively formed in the said body-members.

3. A wire-connector including in combination: two complemental physically-distinct body-members arranged side by side in spaced relationship with respect to each other to provide a passage therebetween for the reception of a line-wire and of a spacer, each of the said body-members being formed with a relatively-large head-portion and with a relatively-slender stem-portion provided with outwardly-facing threads, each of the said body-members being formed in its head-portion with a branch-wire passage extending in a direction crosswise of the passage between the two said body-members and intersecting the said passage; a clamping-nut engaging with and embracing the respective threaded stems of the two said body-members; and a spacer interposed between the two said body-members to hold the respective threaded stem-portions thereof in engagement with the said clamping-nut.

4. A wire-connector including in combination: two complemental physically-distinct body-members arranged side by side in spaced relationship with respect to each other to provide a passage therebetween for the reception of a line-wire and of a spacer, each of the said body-members being formed with a relatively-large head-portion and a relatively-slender stem-portion provided with outwardly-facing threads, each of the said body-

members being formed in its head-portion with a branch-wire passage extending in a direction crosswise of the passage between the two said body-members and intersecting the said passage; a clamping-nut engaging with and embracing the respective threaded stems of the two said body-members; and a clamping-shoe engaged by the said clamping-nut and constructed and arranged to be moved thereby toward the branch-wire passages respectively formed in the head-portions of the two said body-members.

5. A wire-connector including in combination: two complemental physically-distinct body-members arranged side by side in spaced relationship with respect to each other to provide a passage therebetween for the reception of a line-wire and of a spacer, each of the said body-members being formed with a threaded portion of substantially-semicircular form in cross section with the threads thereon facing away from the threads of the other of said body-members, each of the said body-members also being formed with a branch-wire passage extending in a direction crosswise of the passage between the two said body-members and intersecting the said passage therebetween; a clamping-nut embracing and engaging with the respective threaded portions of the two said body-members; and a spacer interposed between the threaded portions of the two said body-members to hold the same in engagement with the said clamping-nut.

6. A wire-connector including in combination: two complemental physically-distinct body members arranged side by side in spaced relationship with respect to each other to provide a passage therebetween for the reception of a line-wire and of a spacer, each of the said body-members being formed with an outwardly-facing threaded portion and each thereof being formed with a branch-wire passage extending in a direction crosswise of the passage between the two said body-members and intersecting the said passage; a clamping-nut engaging with and embracing the respective threaded portions of the two said body-members; and a clamping-shoe engaged by the said clamping-nut and constructed and arranged to be moved thereby toward the branch-wire passages respectively formed in the said body-members, the said clamping-shoe also being provided with a wedging-portion engaging with one of the said body-members to force the same away from its complemental body-member when the said clamping-shoe is moved by the said clamping-nut toward the branch-wire passages in the said body-members.

ARTHUR O. HAVERSAT.
